RANGE FINDER

James C. Chambers, 2045 N. Sinaloa St., Altadena, Calif.

Filed May 11, 1961, Ser. No. 65,124

Term of patent 14 years

(Cl. D52—6)

FIG. 2.

FIGURE 1 is a perspective view of the front of the range finder, and FIGURE 2 is a perspective view of the back of the range finder.

The essential features of the design reside in the portions shown in full lines.

I claim:

The ornamental design for a range finder, as shown and described.
